INTERFERENCE ELIMINATION SYSTEM

Joseph Sedlmayer, Berlin-Charlottenburg, Germany, assignor to Siemens & Halske, Aktiengesellschaft, Siemensstadt, near Berlin, Germany, a corporation of Germany

Application May 17, 1934, Serial No. 726,038
In Germany April 12, 1933

2 Claims. (Cl. 250—8)

The present invention relates to a method of and means for eliminating interference in the electric signal communication systems wherein messages are transmitted by means of impulse signals, as for example, in alternating current telegraphy. It is suitable for the transmission over wires as well as over wireless paths. The advantage derived from the invention lies in the fact that interferences of the most various types 5 are caught and removed simultaneously with the result that an actually reliable transmission of messages is guaranteed.

It is known in the field of wireless communication, particularly in the short-wave art, that 10 interference phenomena exist in the form of selective fadings which make their existence known by the variation of the intensity only of a part of the frequencies of a transmitted frequency band. Attempts have heretofore been made to 15 eliminate the influence of fading on this type by emitting simultaneously, or modulating upon a joint carrier wave several frequencies, for instance a fundamental wave and harmonic waves of the same frequency. Then again, there are 20 interferences which produce additional currents in the receiving apparatus and which, for instance in wireless transmission, are caused by atmospheric influences. For the purpose of reliable reception for this case, the prior art has 25 proposed the use of a so-called double tonal control, i. e. to send one frequency for the signal current and another frequency for the spacing current. In such case there is provided at the 30 receiving end a differential circuit scheme which operates the receiving apparatus with the alternating reception of the two frequencies. Thus the interferences are powerless in that 35 the frequencies used for signal transmission are contained therein which influence simultaneously both parts of the differential circuit so that the receiving apparatus is not actuated. In the transmission by wire, interferences 40 may appear in similar manner, for instances interfering impulses by adjacent lines or by foreign sources of disturbances may be produced, or the transmission characteristics may be temporarily changed for certain frequencies by a 45 switch-over, for example in high tension lines.

According to the present invention, the above 50 listed phenomena which cause interference are eliminated for the same transmission channel by combining with each other the two methods described. In other words, use is made of double tonal control and of several frequencies which 55 are preferably in harmonic relationship, for each the signal current and the spacing current. Moreover, in addition, there is proposed according 60 to the invention a new arrangement for the elimination of the total fading, i. e., such fad-

ings which do not favor special frequencies but which cause a uniform fading of the sound intensity. This is accomplished by connecting level regulating arrangements in those branches in receiving circuits which are separated for the purpose of the elimination of interferences and which act, for instance with respect to the interferences, in opposition to each other or which, when interference occurs, carry different parts of the incoming energy and act integrating on 10 the receiving apparatus. It is further suitable for the purpose of providing a further joint coarse regulation in the joint part of the input of the receiving arrangement. The advantages derived therefrom consist, in the first place, in 15 purging the currents fed to the regulating amplifiers of interferences to an appreciable degree so that these latter can no longer exert a noticeable influence on the adjusting apparatus contained in the branches. In the second place, an 20 advantage must be seen in the fact that with the use of a coarse regulation the adjusting range of the regulators contained in the branches can be kept considerably smaller than without the use of a coarse adjuster. Thus the required input 25 can be held down considerably. By a coupling of the controls contained in the branches the elimination of total fading can be further effected by both regulators jointly, the one of the selective fading by the one or the other regulator 30 which is in the branch wherein the selective fading falls. In this manner the regulators in the different branches may be kept approximately at the same level during the transmission, the additional vernier regulation taking place 35 separately in each branch.

Further details of the invention are explained by means of the accompanying drawing, which is given by way of example:

Fig. 1 shows the frequency scheme of an arrangement according to the invention.

Fig. 2 represents a schematic diagram of the circuit arrangement according to Fig. 1.

Fig. 3 shows closer details of the receiving arrangement according to Fig. 2.

The circuit embodiment shown by way of example is intended for the transmission of telegraphic signals, wherein also currents are transmitted during the signal spaces which have a frequency different from those of the signal currents, in other words, use is made of a so-called double tonal control. According to Fig. 1 the carrier frequency f_t is modulated during the signal current period with a frequency f_1 and its first harmonic frequency $2f_1$ and during the spacing period with a frequency f_2 and its first harmonic $2f_2$. Hence, beside the carrier frequency f_t there are sent during the signal the side frequencies $f_t \pm f_1$ and $f_t \pm 2f_1$ and during the spacing the side frequencies $f_t \pm f_2$ and $f_t \pm 2f_2$. The change be- 50 55 60

tween the two frequency pairs f_1 , $2f_1$ and f_2 , $2f_2$ corresponds to a frequency modulation. The corresponding frequencies of both frequency pairs must be different from each other only so much that a sufficient separation by filter can be effected. Let it be assumed for instance that the frequencies f_1 and $2f_1$ according to Fig. 1 are 1000 Hertz and 2000 Hertz and the frequencies f_2 and $2f_2$ 1200 Hertz and 2400 Hertz.

10 The combination of side band frequencies having harmonic relationship practically removes the influence of the carrier wave fading. With the absence of the carrier frequency, there are produced after rectification at the receiving end, from 15 the side bands only, the transmitted fundamental frequencies and their upper harmonics, for instance according to Fig. 1 the frequencies f_1 , $2f_1$, $3f_1$, and $4f_1$ and f_2 , $2f_2$, $3f_2$ and $4f_2$, respectively. Compared with the standard transmission, only 20 the amplitude of the individual frequencies then change. Since this amplitude variation can be balanced by fading regulation, it is possible to practically eliminate the influence of the carrier wave fading. In order to bring to practical realization the basic idea of the invention, use could 25 be made in place of a fundamental frequency and its first upper harmonic also of a fundamental frequency and several harmonics, or only of the latter alone. It may even be advantageous 30 to employ only frequencies having somehow or other positive relationship with a fundamental frequency and to differentiate signal current and spacing current by variation of the fundamental frequency.

35 According to Fig. 2 there is arranged at the sending side (left) a generator G which produces with opened contact of the sending relay SR 1200 Hertz and with closed contact 1000 Hertz by the addition of a capacity C. Let the last-named frequency correspond to the signal current. The 40 harmonics of the said fundamental frequency are produced by distortion in a strongly biased discharge tube VZ. The net system N serves to filter out the fundamental frequency and the first harmonic and to equalize or make even the 45 amplitudes of both frequencies. The frequencies are then amplified in an amplifier V and modulated onto the carrier frequency (f_1 in Fig. 1) in the modulator M. The carrier frequency is 50 amplified in the emitting amplifier S and radiated from the transmitting antenna SA.

At the receiving end the carrier frequency is received by the receiving antenna EA and demodulated in receiver E. Connected to receiver 55 E is a coarse regulator RG. The produced modulation frequencies which correspond to the frequencies produced at the sending end by generator G or distorting VZ respectively are then 60 filtered through four band filters. The outlets of the band filter for 1000 and 2000 Hertz lead to a branch V1 of the adjusting amplifier RV, the outlets of the filters for 1200 and 2400 Hertz to a branch V2. The adjusting amplifier has three 65 stages or steps of which the last is arranged as rectifier. At the outlet of the rectifier step is disposed the receiving relay ER in differential circuit arrangement in such manner that interference amplitudes arriving simultaneously in the signal and spacing current channel do not bring 70 the relay to response.

The two adjusting amplifiers disposed in the low frequency channels V1, V2 are presumed to have such a relationship to each other that the regulator V2 disposed in the spacing channel is 75 entrained by regulator V1 and operates in the

same sense when the latter responds and vice versa. This coupling has the following purpose: If it is desired that all distortions which the signal undergoes during transmission should be compensated to the most possible degree, the 5 duration of adjustment of each regulator must not exceed the duration of an elementary signal even for the maximum occurring level variations. If the regulators were independent of each other, the result would be that the regulator disposed 10 in the non-used channel at that particular moment would respond, bringing the distortion level, alone present in its inlet, to the theoretical value proscribed for the signal. In this manner, the distance between used level (in the used channel) 15 and distortion level (in the unused channel) would be so much shorter as to interfere with a reliable working of the differential relay. In accordance with the invention the regulator disposed in the used channel shifts with the response at the same time as the grid biasing potential of the regulator in the unused channel to such a degree that the latter cannot be made to respond at all from the distortion level alone. This locking is only released when the useful 20 amplitude drops in the first regulator and when it jumps over the second channel whose regulator now again locks the first. The regulation of the total fading is done by both regulators jointly and the one of the selective fading by the regulators 25 individually, both regulators being approximately at the same level during the transmission, only the additional fine regulation taking place individually in each channel.

The arrangement of a coarse regulator RG 30 further accomplishes that the total level which is fed to the band filters Bf, has already experienced a certain regulation. Such a coarse regulation assures a smaller regulation range of the regulators disposed in the branch channels, 40 considerably smaller than in the case where the vernier regulators had to take up the entire regulating task. The necessary input can therefore be kept in closer limits. It is not essential whether the coarse regulator is arranged before or 45 behind the demodulator and care must only be taken regarding its dimensioning that jumpy variations of the arriving field intensity are regulated during a time period which is small compared to the time period of an elementary signal. 50

The band filters Bf must be dimensioned so that the alternating currents fed to the regulation amplifiers V1, V2 are already sharply filtered out. The action of additional interference impulses with respect of regulation amplifiers V1, V2 is 55 greatly lessened by means of such an arrangement.

Fig. 3 shows an exemplified embodiment of the regulating amplifier sets V1, V2 being coupled with each other. The amplifier V1 comprises the two series-connected amplifier tubes RV1, RV2 and the rectifier tube G1; and the amplifier V2 similarly comprises the tubes RV1', RV2' and G1'. The outputs of the band-pass filters Bf1, Bf2, designed for 1000 and 2000 cps (corresponding to 60 signal current), are united by way of the input 65 transformers U1 with the grid circuit of tube RV1, and the band-pass filters Bf3, Bf4, designed for the frequencies 1200 and 2400 cps, are similarly associated by way of the transformer 70 U1' with the grid circuit of the tube RV1'. In the grid circuit of each of the two tubes is included a capacity resistance circuit scheme C1, R1, and C1', R1', respectively, by which, upon the 75 arising of grid current, there is occasioned a "dis-

placement" voltage as a function of the amplitude or strength of the incoming current impulses. For instance, as soon as a signal current comes in, that is to say, as soon as currents flow through the band-pass filters $Bf1$, $Bf2$, there flows also a grid current in the tube $RV1$ which causes a fall of potential across the resistance $R1$ such that the tube becomes negatively biased. In other words, the working point is shifted towards the lower knee. The stronger the currents flowing through $Bf1$, $Bf2$, the more will the working point of the tube $RV1$ be shifted downwards, and the lower will become the gain of the tube $RV1$. However, inasmuch as the amplitude of the grid voltage will grow at the same time, conditions may be so made that, if a state of proper balance or adaptation is created, the amplitude by and large will be fairly stabilized at the output end of the tube $RV1$. The output of the latter tube is in inductive coupling relationship with the amplifier tube $RV2$, while the output circuit of this last-named tube, in turn, is inductively coupled with the rectifier tube $G1$. In the grid circuits of the tubes $RV2$ and $G1$ are included the same stabilizing arrangements as in the grid circuit of the tube $RV1$, i. e., $C2$, $R2$, and $C3$, $R3$, respectively. As a result of this cascade arrangement of the regulator means, the sensitiveness of the regulatory action or the degree of constancy of the output amplitude, is enhanced to an extraordinary extent. The same thing holds good for the tubes $RV1'$, $RV2'$, $G1'$ of the amplifier end $V2$. In fact, the grid circuits thereof contain corresponding regulating means denoted by $C1'$, $R1'$, and $C2'$, $R2'$, and $C3'$, $R3'$.

The grid circuits of the tubes $RV1$, $RV1'$, and $RV2$, $RV2'$, respectively are, in addition, coupled each by a resistance $W1$ and $W2$, respectively, with the result that the regulation of the tubes $RV1$, $RV1'$, and $RV2$, $RV2'$ is rendered independent of each other. This independence consists in that whenever an impulse current flows through one end $V1$ or $V2$, the respective other branch or end $V2$ or $V1$, as the case may be, is blocked for the passage of an impulse. For instance, if current flows through the band-pass filters $Bf1$, $Bf2$, the grid current above referred to also causes, by way of $R1$, a fall of potential across $W1$, and this occasions, at the grid of tube $RV1'$, a negative biasing voltage so that by interference or stray currents liable to reach the grid of the tube $RV1'$ by way of the band-pass filters $Bf3$, $Bf4$, practically no current will be caused to flow in the plate circuit of the tube $RV1'$. A choke capacity arrangement $D1$, $K1$, and $D1'$, $K1'$ is arranged in parallel relation to the resistance $W1$. The capacities $K1$, $K1'$ serve the purpose of short-circuiting the resistance $W1$ for the currents coming from the band-pass filters in order that the currents operative at the grid of one of the tubes $RV1$, or $RV1'$ by way of the coupling through resistance $W1$, may not, at the same time, be able to reach the grid of the respective other tube $RV1$ or $RV1'$. This short-circuiting action is increased and promoted by the aid of the choke-coils $D1$, $D1'$, these latter being so dimensioned (voltage division) that, of the voltage arising across the terminals of the capacities $K1$ and $K1'$, only a small portion will be able to become active across the resistance $W1$. The same thing holds true of the tubes $RV2$, $RV2'$ ($W2$, $D2$, $K2$, and $W2'$, $D2'$, $K2'$).

The choke capacity schemes $A1$, $C11$, and $A2$, $C22$, and $A1'$, $C11'$, and $A2'$, $C22'$, respectively,

serve, as known from the prior art, for the purpose of precluding the plate alternating current from the plate supply battery and of preventing coupling of the tubes with one another by way of the plate supply. The grid voltage of the rectifier tubes $G1$, $G1'$ is additionally produced by a supplementary direct current voltage which is tapped at the voltage dividers Sp and Sp' , respectively, as shown in the drawing. Each of the outputs of the rectifier stages contains the 10 winding of the receiving relay ER which thus is connected differentially. For smoothing the direct current there are provided the filter schemes $A3$, $C41$, $C42$, and $A3'$, $C41'$, $C42'$, respectively.

As has already been pointed out, what is realized by a circuit arrangement as hereinbefore disclosed is that, as long as one of the amplifier branches or ends is traversed by an impulse, the respective other amplifier branch is non-transmissive. To be sure, this inter-dependence is obtainable also by the use of other suitable ways and means, say by the coupling through resistances $W1$, $W2$, etc., or by coupling through suitable tube arrangements. It is also feasible that 25 instead of filter schemes $D1$, $K1$, etc., multi-mesh chains or networks are used. The time constants of the regulator circuits $C1$, $R1$, and $C1'$, $R1'$ may moreover be determined and fixed independently of the time constants of the coupling means $W1$, 30 $D1$, $K1$, $D1'$, $K1'$.

I claim.

1. In a radio telegraph system, the method of eliminating interference in communication which comprises modulating a high frequency carrier 35 frequency by an audio frequency current and its first harmonic during a signalling period, modulating the same carrier by a different audio frequency current and its first harmonic during the spacing period, radiating the resultant energy, 40 receiving the energy and selectively separating out the two audio frequencies and their respective first harmonics, passing one audio frequency current and its first harmonic through one path and the other audio frequency current and its 45 first harmonic through another path, and differentially recording the passage of said energy through said two paths.

2. A telegraph system comprising, in combination, a signal relay having two positions of 50 operation, an oscillation generator responsive to one position of said relay to generate one frequency and to the other position of said relay to generate another frequency, a distorting device in circuit with the output of said generator producing a harmonic of both said frequencies, a filter connected to said distorting device for enabling the passage therethrough of said two frequencies and their harmonics, an amplifier for amplifying said two frequencies and their harmonics, means for modulating a carrier wave by 55 said two frequencies and their harmonics and for transmitting same, a receiver having filters for separately filtering out and passing said two frequencies and their respective harmonics, a differential relay having two windings, means for applying one of said filtered frequencies and its harmonic to one of said windings and the other frequency and its harmonic to the other winding, 60 whereby interfering currents received by said receiver affect both windings of said relay equally 65 and in opposite sense.

JOSEPH SEDLMAYER.
